Primary Examiner—M. N. Pandozzi

CLAIM

The ornamental design for a pinched trainer cup, as shown.

DESCRIPTION

FIG. 1 is a perspective view of a first embodiment of a pinched trainer cup showing our new design; FIG. 2 is a front elevational view of the first embodiment; FIG. 3 is a rear elevational view of the first embodiment; FIG. 4 is a right side elevational view of the first embodiment;

FIG. 5 is a left side elevational view of the first embodiment; FIG. 6 is a top plan view of the first embodiment; FIG. 7 is a bottom plan view of the first embodiment; FIG. 8 is a perspective view of a second embodiment of a pinched trainer cup, having a different cap from the first embodiment;

FIG. 9 is a front elevational view of the second embodiment; FIG. 10 is a rear elevational view of the second embodiment; FIG. 11 is a right side elevational view of the second embodiment;

FIG. 12 is a left side elevational view of the second embodiment; FIG. 13 is a top plan view of the second embodiment; and, FIG. 14 is a bottom plan view of the second embodiment.
